CLUTCH FOR DRILL HEADS

Andrew B. Crichton, Jr., Johnstown, Pa., and Carl G. Wennerstrom, Chicago, Ill.; said Wennerstrom assignor to The Crichton Company, Johnstown, Pa., a corporation of Delaware

Application October 11, 1948, Serial No. 53,903

6 Claims. (Cl. 192—20)

1

This invention relates to a drill head especially applicable in coal mining and other relations of the general character disclosed in our pending applications, Serial No. 6,236, filed February 4, 1948, for Coal Mining Apparatus; Serial No. 21,893, filed April 19, 1948, for a Power Take-Off System and Apparatus; and Serial No. 21,894 for a Drill Head.

An important object is to produce, as in said applications, irrespective of any particular source of power, a drill head wherein the torque capacity of the clutch which controls the operation of the auger, in order to enhance safety of operation, will be in direct proportion to the amount of pressure manually exerted in applying the drill head, enabling the miner to feel his way along as he drills and exert just enough pressure to revolve the auger, any sticking or jamming of the drill causing slipping of the clutch.

While it is generally aimed to provide a construction which attains the objects and aims disclosed in the mentioned applications, it is also aimed to provide a novel clutch mounting, lever-controlled mechanism for applying the clutch against slippage; a novel casing which may be more readily manipulated to position the drill in starting, and a novel detail construction generally.

Various additional objects and advantages will in particular be pointed out and otherwise become apparent as this description progresses, taken in connection with the accompanying drawings illustrating one operative embodiment by way of example. In said drawings:

Fig. 1 is a plan view of a drill head constructed in accordance with the invention;

Fig. 2 is a front or drill-end view of such drill head;

Fig. 3 is a substantially longitudinal sectional view on an enlarged scale taken on the line 3—3 of Fig. 2; and

Fig. 4 is a cross-section taken on the line 4—4 of Figure 3 with a fragment of the flexible drive shaft added.

Referring specifically to the drawings, wherein like reference characters designate like or corresponding parts throughout the different views, 10 designates a light-weight casing adapted to be manually held in operation by means of diametrically opposite handles 11, to apply a coal drilling auger or other tool (not shown) driven by a hollow drive shaft 12, and attached thereto by suitable means engaging screw-threads 13, for example.

2

Said casing 10 may comprise two or more separate sections such as a main section 14 and a generally flat cover or closure section 15 secured together as by screws 16. Aligned hubs 17 and 18 extend outwardly from the said sections and suitably, rotatably and slidably mount the aforesaid tool drive shaft 12 at portions 19 and 20 located on opposite sides of a clutch generally designated C, and which includes, rigid with the shaft 12, a clutch section 21 provided by an initially separate hub ring 22 and a clutch head 23. Clutch C also includes a large section or plate 24 having a hub 25 concentric with shaft portion 20 and an opposed large section or plate 42, with a ring gear 26 interposed, such clutch parts being separably secured together by screws or bolts 26^a and collectively form a large hollow gear wheel, either oiltight or open. Said ring gear 26 is provided with external gear-teeth 27.

20 Said ring-gear 26 drives shaft 12 to operate the coal cutting auger under control of the said clutch C. Enmeshed with teeth 27 are the teeth of a "slow speed" gear wheel 28 formed integral with a stub shaft 29 removably journaled in bearings 30 on the sections 17 and 18 and preferably directly in needle or roller bearing structures 31.

25 Keyed on shaft 29 is a "high speed" pinion 32 enmeshed with a "high speed" pinion 33 (Fig. 2) keyed to a driving shaft 34 coupled in unitary relation with and driven by a flexible shaft 35, such shaft 34 being journaled in a bearing 36 in casing section 15 and in ball or needle-bearing structure 37 partly and removably disposed in a bearing opening 38 in casing section 14. Said shaft 34 with pinion 33 thereon and said part of structure 37 are applicable and removable through said opening 38.

30 Said flexible shaft 35 is adapted to be driven from any suitable source of power and especially from a short wall coal-cutter or other means necessarily employed in mining operations, as in our previously identified applications for patents.

35 Reverting to clutch C, it is preferably of the friction type employing a series of separate rings or disks 39 arranged for frictional engagement with each other and alternately having guided engagement at marginal notches with the aforesaid screws or bolts 26^a and with any number of splines or keys 41 carried by ring gear 26 and hub ring 22.

40 The casing 10 is adapted to be filled with lubricant as through an opening in cover 15 normally closed by a screw-plug 15^a which is partially or

entirely excluded from the clutch C by the aforesaid plate 42.

This plate 42 has an integral outwardly extending hub 43 extending into hub 17 in which shaft portion 19 is journaled. Said plates 24 and 42 and ring gear 26 coact in balancing the structure at opposite sides of the clutch and they respectively bear against the inner faces of the hubs 18 and 17. Hub 43 on both the inner and outer faces has attached thereto or loosely provided, suitable ring linings or bearings 44, while hub 25 on its inner face has attached thereto or loosely provided a suitable ring lining or bearing. Plate 42 may be loosely journaled or float or be relatively fixed as preferred. The hub 17 is sealed against the escape of lubricant in any suitable manner as by means of one or more ring gasket-washers 46.

Said hub 25 is journaled in a ball-bearing device or structure 58 of such size as to take the thrust imposed by the drill or auger, and which is mounted in an inwardly extending mounting ring 48a of greater diameter than hub 18 and integral with casing section 14. Hubs 18 and 25 greatly strengthen the casing section 14.

Said shaft portion 20 is slidable as well as journaled in hub 25 and terminates in a reduced portion 49 which is journaled and has limited sliding movement in a suitable ball bearing or equivalent structure 58. A split ring 53, detachably mounted in an annular groove 54 in ring 22 aids in confining and positioning the clutch rings or disks 39.

A clutch control rod 55 shown as a bolt is disposed slidably in the bore of the tool drive shaft 12, with a head 56 bearing against a plate 57 which in turn abuts the outer end of shaft portion 49 and the adjacent surface of a race of the aforesaid ball bearing device or equivalent structure 58. Control rod 55 at screw-threads 60 is adjustably engaged with the screw-threads of a nut 61 slightly slidable but non-rotatably located in the bore of hollow shaft 12, as by a screw lug 62 threaded to and carried by said shaft and extending into a longitudinal groove 63 of said nut 61. A coil spring 64 surrounds rod 55 bearing at one end against said nut and at its other end against a shoulder 65 in the said bore of hollow shaft 12.

It is to be noted that spring 64 may be compressed or variably tensioned according to the adjustment of the rod 55 and coacting nut 61.

Said rod 55 is adapted to be moved to the right, noting Fig. 3, to correspondingly move the tool drive-shaft 12 to the right, against the tension of the spring 64, and thus apply the clutch section 23 to compact and frictionally bind the clutch rings or disks 39 and thereby apply the clutch. To this end, a tubular mounting member 66 is slidably mounted in the bore of hub 18, preferably projecting slightly outwardly from said bore. The bearing device 58 is in unitary relation and moves with the tubular mounting member 66 bearing at one side against an inwardly extending flange 67 of the latter, and against the other side thereof an interiorly recessed cap 68 abuts, the latter being screw-threaded at 69 to the interior of the tubular bearing member 66. Thus the cap 68 is readily removable to permit access to and adjustment of the rod 55 through the engagement of the head 56.

Any suitable means may be employed to slide the tubular mounting member outwardly or to the right in Figs. 1 and 3 in order that the plate 57 and rod 55 will be correspondingly moved

since one race of the bearing structure 58 abuts said plate 57.

As shown, means to accomplish the result stated consists of a lever 70 which at a U-shaped portion is pivoted at 71 to an exterior lug 50 on the cap 68. Said lever 70 is also pivoted at 74 to a link 75 in turn pivoted at 76 to a lug 79 on said hub 18. Clutch shifting or applying lever 77 terminates in a handle 78 of suitable length arranged relatively close to one of the handles 11 on the opposite side to pivot 71 in order that it may be simultaneously grasped with the latter handle by one hand of the operator when desired.

Attention is called to the fact that hub 17 is of such size and position as to enable engagement by one hand of the operator to facilitate the directing and locating of the drill when starting to drill a hole. Further, to this end, hub 17 has a handle extension 51 and a shoulder 52 at its junction with the hub or handle 17. Safety in using the handle 17-51 is enhanced since no parts are removable outwardly therethrough.

With the parts as in Fig. 3, with one hand engaging the handle 17-51 to guide or position the drill or auger, presuming the clutch C to be in released position, spring 64 is usually neutral or uncompressed whereby plate 57 is maintained in contact with the inner race member of ball bearing structure 58, and this action is augmented through an urge to slide clutch control rod 55 to the left, if such spring 64 is under compression. In this position, said spring being neutral does not bind the clutch section 23 against the friction rings or disks 39 or bind them together. However, when lever 77 is pressed at the handle 78 toward the adjacent handle-rod 11 (as in Fig. 1) the system of leverage and linkage applies the clutch by sliding the tubular mounting member 66 slightly to the right, moving the bearing structure 58 with it, also the plate 57, rod 55, nut 61, compressing or tensioning the spring 64, and slightly moving tool drive shaft 12 to the right and causing clutch section 23 to compact the plates 39 against each other and against the plate 24.

Attention is called to the fact, however, that this operation is not normally necessary in order to apply the clutch, but is useful to increase the clutch pressure and is especially useful when an operator desires to extract an auger or tool from the coal. Should the operator, for any reason let go of the handles 11 while drilling, the apparatus is automatically relieved of pressure and the clutch C is automatically released to avoid injury to the workman or mechanism. At any rate, such spring 64 is adapted to yield at a predetermined degree of tension, as a safety measure, so that the drill-head and drill cannot twist the arms and body of the operator when using the same. The said clutch plates are of such multiplicity and friction contact with each other and with the clutch section 23 and hollow clutch section 24, that mere pressure of the tool head and auger against the coal by manual effort, will slide the tool drive shaft 12 slightly to the right in Fig. 3, thereby compacting the rings or disks 39 and frictionally binding the same and adjacent faces of clutch sections 23 and 24, it being clear that the clutch C will be released upon relief of the pressure through the expansion of spring 64 and the pushing action of plate 57 toward the left in Fig. 3 in view of its contact with bearing structure 58, since the latter moves with the slidable tubular mounting member 66.

Various changes may be resorted to provided they fall within the spirit and scope of the invention. What is claimed is:

1. An apparatus of the class described having a casing, a tool operating shaft rotatably and slidably mounted in said casing, a gear journaled in said casing, means to drive said gear, a bearing device in said casing to take the thrust imposed on said gear in operation, clutch means within the casing between said gear and shaft controlled through the sliding of said shaft, one wall of said casing having an inwardly extending ring flange and an outwardly extending hub, said bearing device being mounted in said flange, said wall having a shoulder within and inwardly of said flange abutted by said bearing device, and mechanism operable exteriorly of the casing to apply the clutch parts including an element slidably in said hub.

2. Apparatus of the class described comprising separable sections forming a casing, each section having an outwardly extending hub integral therewith, a shaft adapted to operate an auger or the like having portions journaled and slidable in said sections, one of said hubs being elongated and serving as a handle to direct and center said shaft, a gear in said casing concentric with and enlarged with respect to said shaft comprising a toothed ring, plates on opposite sides of the ring, means separably securing said plates and ring together, means to drive said gear, one of said plates having a hub journaling one of said portions and in turn journaled in one of the first-mentioned hubs, the latter hub having an interior shoulder, washer means between said shoulder and last-mentioned hub, a clutch head on said shaft opposite to the inner lateral wall of one of said plates, friction clutch means in said gear coacting with said wall and clutch head.

3. An apparatus of the class described having a casing, a shaft rotatably and slidably mounted in said casing adapted to operate an auger or the like, a gear journaled in said casing, means to drive said gear, a bearing device in said casing to take the thrust imposed on said gear in operation, clutch means within the casing associated with said gear and controlled through the sliding of said shaft, said gear including a hub through which said shaft passes, said hub extending into said bearing device, one wall of said casing having an inwardly extending ring flange and an outwardly extending hub, said wall forming a shoulder integral with it and disposed interiorly of said rim flange, the interior diameter of said ring flange being greater than the interior diameter of the latter hub, said bearing device being mounted in said ring flange and abutting said shoulder, and mechanism operable exteriorly of the casing to apply the clutch parts including an element slidably mounted in said last-mentioned hub.

4. An apparatus of the class described having a casing, a shaft rotatably and slidably mounted in said casing adapted to operate an auger or the like, a gear journaled in said casing, means

to drive said gear, a bearing device in said casing to take the thrust imposed on said gear in operation, clutch means within the casing associated with said gear and controlled through the sliding of said shaft, said gear including a hub through which said shaft passes, said hub extending into said bearing device, one wall of said casing having an inwardly extending ring flange and an outwardly extending hub, the interior diameter of said ring flange being greater than the interior diameter of the latter hub, said bearing device being mounted in said ring flange, and mechanism operable to apply the clutch parts including an element slidably mounted in the last-mentioned hub, a bearing device carried by said element, said shaft extending through said second bearing device, a cap securing said second bearing device in said element, and an operating device connected to said cap.

5. Apparatus of the class described comprising separable sections forming a casing, each section having an outwardly extending hub integral therewith, a shaft adapted to operate an auger or the like having portions journaled and slidable in said sections, one of said hubs being elongated and serving as a handle to direct and center a mounted tool, a gear in said casing concentric with and enlarged with respect to said shaft comprising a toothed ring, plates on opposite sides of the ring, means separably securing said plates and ring together, means to drive said gear, one of said plates having a hub journaling one of said portions and in turn journaled in one of the first-mentioned hubs, the latter hub having an interior shoulder, washer means between said shoulder and last-mentioned hub, a clutch head on said shaft opposite to the inner lateral wall of one of said plates, friction clutch means in said gear coacting with said wall and clutch head, the other plate having a hub extension through which said shaft passes, an inwardly extending ring flange integral with the same casing section as the other hub and of a greater interior diameter than the latter hub, a bearing device mounted in the said ring flange, said hub extension passing into said bearing device, and mechanism operable to apply the clutch parts including an element slidably mounted in the last-mentioned hub.

6. An apparatus according to claim 1 having means operable interiorly of the casing and entering the latter adjacent one end of said shaft to apply said clutch means, and means to slidably urge said shaft away from said one end to clutch-releasing position.

ANDREW B. CRICHTON, JR.
